UNITED STATES PATENT OFFICE.

LEWIS R. HEIM, OF DANBURY, CONNECTICUT, ASSIGNOR TO THE HEIM GRINDER COMPANY, OF DANBURY, CONNECTICUT, A CORPORATION OF CONNECTICUT.

APPARATUS FOR GRINDING ROLLS AND THE LIKE.

Application filed February 18, 1921. Serial No. 446,041.

To all whom it may concern:

Be it known that I, LEWIS R. HEIM, a citizen of the United States, and a resident of Danbury, county of Fairfield, and State 5 of Connecticut, have invented an Improvement in Apparatus for Grinding Rolls and the like, of which the following is a specification.

This invention relates to the grinding of 10 rolls and the like. One of the objects thereof is to provide practical apparatus for the above purpose of rapid and efficient action. Another object is to provide apparatus of the above nature in which a high degree of 15 simplicity and security of construction are combined with ready adaptability to meet various conditions of use. Another object is to provide apparatus of the above nature in which there is an automatic corrective 20 action resulting in extreme accuracy in grinding of cylindrical objects. Another object is to provide a simple and practical apparatus of the above-mentioned character in which such an automatic corrective action 25 may be rapidly carried on, and in which such corrective action may be made effective with great rapidity and reliability to cure such defects in the work pieces, such as rolls or the like, as inaccuracies in initial roundness. Other objects will be in part obvious 30 and in part pointed out hereinafter.

The invention accordingly consists in the features of construction, combinations of 35 elements, arrangement of parts, and in the several steps and relation and order of each of the same to one or more of the others, all as will be illustratively described herein and the scope of the application of which will be indicated in the following claims.

40 In the accompanying drawings in which is shown one of various possible embodiments of the mechanical features of this invention,

Figure 1 is a front elevation;

45 Figure 2 is an elevation partially in section taken along the line 2—2 of Figure 1;

Figure 3 is a plan of the apparatus shown in Figure 1 certain parts being cut away in order to disclose the construction more 50 clearly;

Figure 4 is a sectional elevation of driving gearing taken substantially on the line 4—4 of Figure 1 and showing the parts on an enlarged scale;

Figure 5 is a sectional view taken along the line 5—5 of Figure 4;

Figure 6 is a similar view taken along the line 6—6 of Figure 4;

Figure 7 is an enlarged front elevation of supporting means for the articles to be ground, and associated parts;

Figure 8 is a plan view of the supporting means shown in Figure 7;

Figure 9 is a side elevation of the parts shown in Figure 8;

Figure 10 is a longitudinal sectional elevation of a pair of carriages and adjusting mechanism therefor;

Figure 11 is a diagrammatic end view illustrating certain relations of the wheels and work supporting device; and

Figure 12 is a similar view illustrating certain actions in connection with the grinding of the roll.

Similar reference characters refer to similar parts throughout the several views of the drawings.

Referring now to Figure 1 of the drawings in detail, there is shown a supporting frame 10 having mounted thereon in suitable ways 11 and 12 respectively the sliding carriages 13 and 14.

Respectively mounted upon these carriages are what will be termed a grinding wheel 15 and a regulating wheel 16, driven to rotate as indicated by the arrows. The work here shown as a cylindrical roller 17 is mounted upon a suitable supporting device 18 and positioned between the peripheries of the wheels 15 and 16 to be engaged and acted upon thereby.

Turning to Figure 10 of the drawings, there is shown the adjusting means of the carriages 13 and 14 which are provided with bearings 19 for the shafts 20 and 21, which respectively carry the wheels 15 and 16.

The carriage 14 is provided with a downwardly extending boss 22 through which is threaded a shaft 23 held against longitudinal movement by means of the collars 24 resting against opposite ends of the bearing 25 on the frame of the machine.

The threaded portion of shaft 23 extends only throughout such a fraction of the length of the shaft as will give to the carriage 14 the desired range of travel, and the unthreaded portion extends through a sleeve 26 to a hand wheel 27 at the right-

hand end of the machine as viewed in the drawings. It will thus be seen that as the hand wheel 27 is rotated in one direction or the other, the carriage 14 is slid along the 5 ways 12 either toward or away from the center of the machine and correspondingly varies the position of the wheel 16.

The carriage 13 is provided with a boss 28 similar to the boss 22 internally threaded 10 to receive the externally threaded sleeve 26 which extends through the bearing 29 on the frame of the machine and which is held against longitudinal movement by the thrust collars 30. This sleeve is of such length 15 and so threaded as to give the desired range of travel to the carriage 13, but is of course smooth in the bearing 29 and extends to the right to make connection with the hand wheel 31, somewhat larger than the hand 20 wheel 27, so as to adapt these for independent adjustment. By the hand wheel the position of the grinding wheel 15 is readily changed in a direction lengthwise of the machine.

25 Considering now the method of drive of the wheels 15 and 16, it will be seen in Figure 3 of the drawings that their shafts are respectively provided with the driving pulleys 32 and 33. The pulley 32 is driven by 30 a belt 34 which passes under a jockey roller 35 and around the pulley 36 on the main driving shaft 37 journaled in the lower portion of the frame of the machine as shown in Figure 2 of the drawings. The latter 35 shaft is driven from any suitable source of power by means of the belt 38 and tight and loose pulleys 39 and 40. The action of the jockey roller 35 journaled upon the swinging arm 41 which oscillates about a shaft 42 fixed on the frame of the machine, permits the carriage 13 to have its full extent 40 of travel without interfering with the efficient drive of the grinding wheel.

On shaft 37 are fixed a pair of pulleys 43 and 44 respectively opposite a pair of pulleys 45 and 46 which rotate about a fixed shaft 47 adjacent the opposite end of the base of the machine as shown in Figure 1 of the drawings, the details of these latter pulleys being shown in Figure 4 of the drawings. The pulley 33 with its shaft is driven by the belt 48 from a pulley member 49 through the speed-change gearing shown in detail in Figure 4 of the drawings, but it 55 may be noted that by the shifting of the belt 50 from a position connecting the small pulley 43 with the large pulley 45 to a position connecting the relatively larger pulley 44 with the small pulley 46, there is gained a 60 change in driving speed with respect to the speed of the main driving shaft 37. Referring to the details of the mechanism shown in Figure 4, the pulley 45 and pulley 46 have a bearing on a sleeve 51 and are 65 bolted one to another by the bolt 52 so as

to turn as a unit with each other and with the sleeve 51. The bolt 52 has mounted thereon a pair of pinions 53 and 54, the former being slightly larger and these pinions are carried around with the pulleys 70 45 and 46 rotating freely on the bolt. The pinion 53 meshes with a gear 55 which is fixed to a sleeve 56, the latter being in turn keyed as at 57 to the fixed shaft 47 and thus held against rotary movement. The pinion 75 54 meshes with a gear 58 which is slightly smaller than the gear 55 and which is fixed to a rotatable sleeve 59. Thus as the pulleys 45 and 46 are driven, the pinions 53 and 54 revolve about the axis of the shaft 47 as 80 well as rotate on the bolt 52. Due to the slight inequality of the sizes of these pinions and of their mating gears, and to the fact that the gear 55 is held against rotation, there is brought about an extremely slow 85 rotation of the gear 58 to compensate for this inequality. Thus for each revolution of the pinions about the axis of the shaft 47 there is a movement of perhaps one or two teeth in extent of the gear 58, the direction 90 of this movement being determined by the direction in which the parts are driven.

The sleeve 59 has fixed thereon as at 60 a clutch member 61 adapted to co-act with an internal clutch surface 62 formed on the 95 pulley 49. Furthermore, the pulley 45 is provided with a clutch portion 63 adapted to co-act with an internal clutch surface 64 which is likewise formed on the pulley 49. In this manner the pulley 49 is provided 100 with two clutch members with which it may alternatively make connection; one of them, the clutch member 63, being always driven at high speed from its direct connection with the pulley 45, and the other, the member 61, 105 being always driven at low speed from its connection through the gearing above set forth. In order to make this alternative connection, the pulley 49 is slidable in the direction of the axis of the shaft 47 and is provided with a grooved hub 65 into which fits a hook 66 having threaded therein an adjusting shaft 67 held against longitudinal movement and operated as by the hand wheel 68 at the front of the machine.

110 It may be noted at this point that the shaft 47 as best shown in Figure 4 of the drawings, is inclined with respect to the horizontal and that the shaft 21 with its bearings is given a similar fixed inclination. This 115 inclination and its effect on the showing of the wheel 16 is so slight that to avoid confusion of lines, it is not indicated in certain figures of the drawings as its representation would give rise to confusion. The 120 relation of the wheels 15 and 16 however, due to this inclination is shown in an exaggerated diagrammatic form in Figure 11 of the drawings and its function and advantages will be hereinafter described.

By the means above described, the wheel 16 may be normally driven at extremely slow speed through the gearing shown in Figure 4 of the drawings and this speed 5 may be slightly altered to meet changing conditions by the shifting of the belt 50 without change in the speed of the main driving shaft 37. By slight adjustment of the hand wheel 68, however, this slow drive 10 is broken and a frictional connection immediately made, whereby the wheel 16 is driven at a speed approximately that of the wheel 15. A free movement of the carriage 14 with the wheel 16 is permitted by the jockey 15 roller 69 similar in construction and action to the jockey roller 35.

Considering now the supporting means for the work, it will be seen that the latter rests upon a hard steel insert 70 in the upper surface of a carrier or plate 71 as shown 20 in Figure 7 of the drawings. This carrier 71 is supported by a pair of bolts 72 and 73 which pass through vertical slots 74 and 75 in supporting plates or posts 76 and 77 secured to a bed as shown in Figure 9 of the drawings. The wedge 79 is interposed between the carrier 71 and is slidably mounted within similarly inclined guides 80 formed on the bed 81 which in turn rests on 30 a rigid portion of the machine. The bed 81 is bolted to a rigid portion of the machine as at 82, the bolt passing through a slot 83 into a threaded opening 82^a whereby the entire supporting device is movable to the right 35 or left for purposes of adjustment. The entire bed 81 and its associated carrier 71 may be raised vertically by engaging the bolt 82 in the upper threaded opening 82^b provided in the bridge portion 103 in addition to the opening 82^a. A vertical adjustment of the roll support may be gained by means of a hand screw 83 threaded into the member 81 and having a collar 84 interlocking with the wedge 79. Thus as this hand 40 screw is turned by means of the grip 85, the wedge 79 is either drawn forwardly or forced toward the rear, giving a corresponding upward and downward movement of the parts supported thereon. Suitable graduations 45 may be provided for giving a visual indication of the height of the carrier 71 and may be conveniently placed upon the wedge 79 as indicated at 79^a. Also a vertical adjustment of the member 71 may be gained 50 by means of the slotted connection through the bolts 72 and 73 whereby either or both ends may be raised or lowered. This gives a capacity of varying the support angularly 55 with respect to the horizontal, for the purpose hereinafter described.

It may also be noted that the wedge 79 may be readily replaced by another wedge having differently inclined supporting surfaces so that a different normal inclination 60 of the carrier 71 may be provided irrespec-

tive of the angular adjustment facilitated by the bolts 72 and 73.

Clamped at each side of the member 71 by means of the bolt 72 passing through suitable openings therein are a pair of guides 86 and 87, the latter of which is provided with set screws 88. These set screws permit of an accurate adjustment of the plate 87 toward or away from the plate 86 in order to fit these guides suitably to different 75 diameters of rolls to be ground. The bolt 72 being loosened to the desired extent, the set screws 88 are driven in until it swings outwardly the upper end of the plate 87 to fit the roll, and at the same time clamp the various parts in position. These guides are so positioned as to feed the rolls, however short, up into a position in which they are gripped between the grinding and regulating wheels. The guide plates 86 and 87 may 80 be adjusted vertically by causing the bolt 72 to engage the auxiliary openings 86^a therein.

The bolt 73 is likewise provided with a pair of guides 89 and 90, the latter having a set screw 91 functioning in a manner substantially identical with that of the set screws 88, and the guides 89 and 90 may also be adjusted vertically by engaging the bolt 73 with the auxiliary openings 89^a in the plates. The guides 89 and 90 receive 95 the rolls just as they pass out from the grip of the wheels so that however short and however many rolls are acted upon at once, they are securely led up to and away from the grinding wheel.

Considering now the action whereby the rolls are fed along the carrier between the wheels, reference is again made to Figure 11 of the drawings and to the inclination with respect to the horizontal of the regulating wheel. This latter wheel which travels at slow speed, exerts a much greater frictional effect on the rolls than that of the high speed grinding wheel which cuts off the metal of the roll which is brought 105 into contact therewith. Accordingly the regulating wheel not only causes a continuous rotation of the rolls about their own axes by lifting the adjacent side of the roll while the opposite side is forced downwardly by the grinding wheel, but also when inclined with respect to the position of the roll, exerts a lateral thrust thereon, tending to urge them longitudinally of the carrier 71. The fixed inclination of the regulating wheel with respect to the horizontal may be in the neighborhood of three degrees which if the carrier were in a horizontal position, would give a maximum rate 115 of feed of the work. This is illustrated in 120 Figure 11 of the drawings in which, as before noted, the inclination of the regulating wheel is much exaggerated. The carrier in this position of maximum speed of feed is horizontal, as indicated in full lines.

If 130

however the carrier were tilted into the dotted line position, there would be no feeding action by the regulating wheel for its path of travel would be at right angles 5 with the path of travel of the rolls. Thus by varying the inclination of the carrier between these extremes, any desired rate of feed of the rolls may be attained, all without moving or adjusting the regulating 10 wheel.

It will be understood also that the carrier may be tilted in the reverse direction from that hereinbefore noted so as to obtain a still greater rate of feed of the rolls than 15 the maximum rate of feed hereinbefore noted. It may moreover be noted generally that the work support or carrier pre-determines the path of travel in an axial direction of the work or rolls relative to the 20 operative surfaces of the two wheels, and aside from performing this important function also acts to take up the thrust of the grinding wheel on the work or rolls or to support or hold the work against such a 25 thrust; the work support or carrier thus prevents the work from being displaced out of the position which it is intended to have with respect to the two wheels or prevents the work from being moved out of its intended 30 path of travel in a general axial direction, and thus the work is properly supported in operative relation to the two wheels; the terms "work support" or "carrier" therefore are to be understood as con- 35 templating and including therein any suitable or appropriate arrangement for performing such functions as just pointed out.

Another feature of the grinding action is diagrammatically illustrated in Figure 12 40 of the drawings. The regulating wheel 16 is mounted higher than the grinding wheel 15. The difference in elevation is exaggerated in Figure 12 of the drawings but it may be noted that the axis of the regulating wheel 45 is substantially equal in height to that of the center of the work, whereas the grinding wheel is materially below. With the parts in this position, if an irregularity or projection in the surface of the roll be assumed to engage the regulating wheel, its engagement does not result in a corresponding 50 movement of the work toward the grinding wheel with the grinding of a flat or depression on the opposite side of the roll. The outward pressure of the work due to this engagement is in a horizontal direction, which direction is not radial to the 55 grinding wheel and hence even if the roll moved horizontally, there would be a much smaller imperfection cut into its opposite side due to the curvature of the grinding wheel. In this manner, imperfections may 60 be reduced and gradually done away with as the rotating work passes between the 65 wheels.

It is also to be noted that the upper surface of the carrier 71 inclines upwardly toward the grinding wheel. This conformation of the parts results in a raising of the work as it is forced in a direction away 70 from the regulating wheel by the engagement of a projecting part with the surface of the regulating wheel. By a proper degree of inclination of this supporting surface, the work may be raised to just such 75 desired extent as to prevent injury thereto due to its lateral movement caused as above.

Either or both of these features may be used and both are singly highly beneficial, and either alone is highly beneficial although 80 it is preferred for best results to use both. The degree of inclination given the supporting surface hereinbefore described also has the tendency to cause the work to be held 85 in contact with the regulating wheel by the action of gravity, and this insures a uniform rate of rotation of the work.

Another feature of construction of this apparatus is the arrangement of a single protective casing providing the two hood 90 portions 92 and 93 for encasing respectively the grinding wheel 15 and the regulating wheel 16. The single casing enclosing the wheels is rigidly secured to the frame 10 of the machine by suitable means such as 95 the bolts 101 and is of such extent that ample movement of the wheels 15 and 16 due to their adjustable carriages 13 and 14 may take place within the casing and without necessitating a corresponding movement of 100 the hood sections 92 and 93 respectively. The casing is provided with suitable slots 102 in the wall adjacent the bearings in 105 the carriages 13 and 14 so as to permit of the relative adjustment of the wheels 15 and 16 within the casing throughout the desired range, the shafts 20 and 21 passing through 110 these slots. The front portion of each hood section 92 and 93 is provided with a cover plate 94 which is removably held in place by means of a latch 95^a and a wing nut 95. Thus ready access to the wheels is provided.

The lower portion of the casing providing the hood portions 92 and 93 is provided 115 with a horizontal bridge section 103, more clearly shown in Fig. 9, upon which is mounted the bed 81 of the support for the work carrier 71. The rear wall of the casing is provided with a suitable opening 120 through which a rearwardly extending portion of the carrier 71 may extend to discharge the work after operation thereon by the wheels into a downwardly and forwardly 125 extending chute 96 formed in the frame of the machine and leading to an opening 97 at the front of the frame 10. Beneath the opening 97 there is suspended as by the hooks or lugs 98 on the pins 99 a removable receptacle or reservoir 100 which contains 130

a suitable liquid into which the finished work or rolls may be dropped without injury. A wire basket 104 is suspended within the receptacle 100 by means of which the 5 rolls may be conveniently removed from the cushioning liquid independently of the liquid itself. This arrangement is of particular importance as it permits the return of the work or rolls to the front of the 10 machine as fast as they are completed or operated upon and are thus placed within ready reach of a workman stationed at the front of the machine in order that he may conveniently examine the result of the work 15 which is being done.

Referring particularly to Figs. 1 and 2, there is mounted upon the back of the detachable receptacle or reservoir 100 a pump housing 105 in the lower end of which is 20 rotatably mounted a suitable pump member preferably of the centrifugal impeller type. The pump housing 105 is extended upwardly to provide a hollow casing 106 in the upper end of which is formed a bearing 108 adapted 25 to rotatably support the shaft 109 for driving the impeller in the base portion of the casing 105. A suitable opening 107 connected with the receptacle 100 is adapted to conduct the liquid from the receptacle 30 to the central or axial region of the impeller within the casing 105 which is provided at a suitable circumferential point with an outlet with which a suitable pipe connection 117 is connected for circulating the liquid. 35 The pipe connection 117 leads to the pipe 118 extending downwardly through the protective casing about the wheels 15 and 16 for conducting the liquid, which may be any suitable cooling liquid, to the operative surfaces of the wheels acting upon the work. 40 The cooling liquid is returned to the reservoir 100 by means of chute 96. A substantially constant level is thus maintained in the reservoir 100 and, by reason of the hole 45 upwardly extending casing 106 being in connection with the reservoir 100, a like level is maintained within the shaft housing 106. The housing 106 provides the bearing 108 for the shaft 109 at a height which is 50 above the level of the cooling liquid and there is thus avoided the necessity of using a stuffing box in connection with the shaft 109, the bearing 108 being at all times above the level of the liquid.

55 At the upper end of the shaft 109 there is mounted a gear 110 adapted to engage the gear 111 mounted on a jack shaft 112 and suitable bearings 113 preferably formed integrally with the pump housing 105 and its 60 extension 106. Intermediate of the pair of bearings 113 there is mounted upon the shaft 112 a pulley 114 which is driven by means of a belt 115 from the pulley 116 mounted on the main driving shaft. The ratios of 65 the gears and of the pulleys are such that a

suitably high speed of the impeller on the shaft 109 is obtained to cause an effective circulation of the cooling liquid.

It will be noted that the pump in being mounted upon the rear of the detachable 70 reservoir 100 is readily removed with the reservoir 100 from the main frame of the machine so that inspection or repair may readily be made. It may also be noted that the liquid in the container 100 functions 75 not only as a cooling medium for the grinding wheels and the work operated upon thereby, but also functions as hereinbefore described to cushion the receptacle 100 so that the finished work or rolls may be 80 dropped therein without injury.

Furthermore, the adjustment of the position of both carriages 13 and 14 is from the same end of the machine, which conduces greatly to convenience and rapidity in view 85 of the large size of machines in use. The rate of drive of the regulating wheel may, moreover, be conveniently altered to a slight extent, and when it is desired to drive it rapidly as for purposes of truing the wheels, 90 a slight adjustment of the hand wheel 68 will bring about this acceleration of drive. The carrier or work support is also conveniently adapted to various sizes and conditions of 95 work and the rate of feed of the work which varies with the depth of cut and other factors, may be conveniently altered without affecting the rate of drive of the machine, or adopting the relatively cumbersome 100 expedient of mounting the regulating wheel for angular movement. Also the automatic correction of errors in the roll without the production of corresponding errors by the grinding wheel is of the greatest value and 105 conduces to the highest accuracy.

It will thus be seen that there is provided apparatus and an art in which the several objects of this invention are achieved and which are essentially practical in their 110 nature.

As various possible embodiments might be made of the mechanical features of the above invention, all without departing from the scope of the invention, it is to be understood that all matter herein set forth or 115 shown in the accompanying drawings is to be interpreted as illustrative and not in a limiting sense.

I claim:

1. In apparatus of the general nature of that herein described, in combination, a grinding wheel adapted to be rotated at a relatively high speed, a regulating wheel adapted to be rotated at a relatively low speed, a carrier extending between the operative surfaces of said wheels for supporting a substantially round body in operative relation to said wheels, said regulating wheel being adapted to control the rotation of 120 said body on the carrier during the grinding 125

action thereon by the grinding wheel, and said carrier having a supporting surface which makes an obtuse angle with a plane tangent to the grinding wheel surface at the 5 line of contact between the grinding wheel surface and the round body and adapted to permit said body, when irregularities thereon are engaged by the regulating wheel, to move into an increasing space between the 10 grinding wheel and the regulating wheel.

2. In apparatus of the general nature of that herein described, in combination, a grinding wheel adapted to be rotated at a relatively high speed, a regulating wheel 15 adapted to be rotated at a relatively low speed, said wheels being adapted to present operative surfaces traveling in opposite directions, a carrier between said wheels for supporting a cylindrical body in operative 20 relation thereto, the path of travel of the operative surface of the regulating wheel being inclined with respect to the path of travel of the body along said carrier, thereby to feed said body along said carrier, and 25 automatic means for maintaining a substantially constant distance between the axis of rotation of said body and the active portion of the surface of said grinding wheel when said regulating wheel tends to move the 30 axis of said body substantially transversely of the path of travel of said body as said regulating wheel engages irregularities in said body.

3. In apparatus of the general nature of that herein described, in combination, a main frame, a grinding wheel adapted to be rotated at a relatively high speed, a regulating wheel adapted to be rotated at a relatively low speed, said wheels being adapted 40 to present operative surfaces traveling in opposite directions, means providing a movable carriage for mounting said grinding wheel on said main frame, means providing a movable carriage for mounting said regulating wheel on said main frame, a carrier relatively fixed on said main frame and extending between said wheels for supporting 45 round bodies in operative relation to said wheels, a threaded sleeve extending outwardly to one end of said main frame and engaging one of said carriages for manually adjusting said carriage toward or away from said carrier, and a threaded shaft extending outwardly through said sleeve to the 55 same end of said frame and engaging the other of said carriages for manually adjusting said carriage toward or away from said carrier.

4. In apparatus of the general nature of that herein described, in combination, a main frame, a grinding wheel adapted to be rotated at a relatively high speed, a regulating wheel adapted to be rotated at a relatively low speed, said wheels being adapted 60 to present operative surfaces traveling in 125

opposite directions, means providing a movable carriage for mounting said grinding wheel on said main frame, means providing a movable carriage for mounting said regulating wheel on said main frame, a carrier relatively fixed on said main frame and extending between said wheels for supporting round bodies in operative relation to said wheels, and independently operative and coaxial means for separately adjusting each of 75 said carriages toward or away from said carrier.

5. In apparatus of the general nature of that herein described, in combination, a main frame, a grinding wheel adapted to be 80 rotated at a relatively high speed, a regulating wheel adapted to be rotated at a relatively low speed, said wheels being adapted to present operative surfaces traveling in 85 opposite directions, protective means mounted on said frame for substantially enclosing said wheels and adapted to form a bridge extending substantially beneath the adjacent operative surfaces of said wheels, and a carrier extending between said wheels for supporting round bodies in operative relation to 90 said wheels mounted upon said bridge portion of said protective means.

6. In apparatus of the general nature of that herein described, in combination, a main frame, a grinding wheel adapted to be rotated at a relatively high speed, a regulating wheel adapted to be rotated at a relatively low speed, said wheels being adapted 100 to present operative surfaces traveling in opposite directions, protective means mounted on said frame for substantially enclosing said wheels and adapted to form a bridge extending substantially beneath the adjacent operative surfaces of said wheels, a carrier 105 extending between said wheels for supporting round bodies in operative relation to said wheels mounted upon said bridge portion of said protective means, and means for adjusting one of said wheels toward or away from said carrier independently of said protective means.

7. In apparatus of the general nature of that herein described, in combination, a main frame, a grinding wheel adapted to be rotated at a relatively high speed, a regulating wheel adapted to be rotated at a relatively low speed, said wheels being adapted to present operative surfaces traveling in opposite directions, protective means mounted on said frame for substantially enclosing said wheels and adapted to form a bridge extending substantially beneath the adjacent operative surfaces of said wheels, a carrier 115 extending between said wheels for supporting round bodies in operative relation to said wheels mounted upon said bridge portion of said protective means, and means for detachably mounting said carrier on said 120 bridge portion of said protective means.

8. In apparatus of the general nature of that herein described, in combination, a main frame, a grinding wheel adapted to be rotated at a relatively high speed, a regulating wheel adapted to be rotated at a relatively low speed, said wheels being adapted to present operative surfaces traveling in opposite directions, a carrier extending rearwardly of said frame and between said wheels for supporting round bodies in operative relation to said wheels, means for guiding said bodies in a rearward direction from the front of said frame onto said carrier, and a discharge chute adapted to receive said bodies from the grip of said wheels after operation thereon by said wheels and to return said bodies in a forward direction to the front of said frame. 70
9. In apparatus of the general nature of that herein described, in combination, a main frame, a cushioned receptacle mounted on the front portion of said frame, a grinding wheel adapted to be rotated at a relatively high speed, a regulating wheel adapted to be rotated at a relatively low speed, said wheels being adapted to present operative surfaces traveling in opposite directions, a carrier extending between said wheels for supporting round bodies in operative relation to said wheels, means for guiding bodies in a rearward direction from the front of said frame onto said carrier for operation thereon by said wheels, and means adapted to receive said bodies from the grip of said wheels after operation thereon by said wheels and to conduct said bodies into said cushioned receptacle. 80
10. In apparatus of the general nature of that herein described, in combination, a main frame, a receptacle mounted on the front portion of said frame and adapted to contain a cushioning fluid, a grinding wheel adapted to be rotated at a relatively high speed, a regulating wheel adapted to be rotated at a relatively low speed, said wheels being adapted to present operative surfaces traveling in opposite directions, a carrier extending between said wheels for supporting round bodies in operative relation to said wheels, means for guiding bodies in a rearward direction from the front of said frame onto said carrier for operation thereon by said wheels, means adapted to receive said bodies from the grip of said wheels after operation thereon by said wheels and to conduct said bodies into said cushioned receptacle. 90
11. In apparatus of the general nature of that herein described, in combination, a main frame, a cushioned receptacle mounted on the front portion of said frame, a grinding wheel adapted to be rotated at a relatively high speed, a regulating wheel adapted to be rotated at a relatively low speed, said wheels being adapted to present operative surfaces traveling in opposite directions, a carrier extending rearwardly of said frame and between said wheels for supporting round bodies in operative relation to said wheels, means for guiding bodies in a rearward direction from the front of said frame onto said carrier, and a discharge chute adapted to receive said bodies from the grip of said wheels after operation thereon by said wheels and to return said bodies in a forward direction to the front of said frame. 100
12. In apparatus of the general nature of that herein described, in combination, a grinding wheel adapted to be rotated at a relatively high speed, a regulating wheel adapted to be rotated at a relatively low speed, a carrier extending between the operative surfaces of said wheels for supporting a substantially round body in operative relation to said wheels, said regulating wheel being adapted to rotate said body and said grinding wheel providing an operative surface inclined away from said carrier for action on said body, and means for causing different portions of said inclined operative surface of said grinding wheel to operate upon said body when said regulating wheel engages an irregularity in said body. 110
13. In apparatus of the general nature of that herein described, in combination, a grinding wheel adapted to be rotated at a relatively high speed, a regulating wheel adapted to be rotated at a relatively low speed, a carrier extending between the operative surfaces of said wheels for supporting a substantially round body in operative relation to said wheels, said regulating wheel engaging said body on one side thereof and adapted to rotate said body and said grinding wheel engaging said body substantially on the other side thereof and adapted to perform a grinding action thereon, and automatic means for maintaining a substantially constant distance between the axis of said body and the operative portion of the surface of said grinding wheel while said regulating wheel moves the axis of said body during engagement thereby with irregularities in said body. 120
14. In apparatus of the general nature of that herein described, in combination, a peripheral grinding wheel adapted to be rotated at a relatively high speed, a regulating wheel adapted to be rotated at a relatively low speed, said wheels being adapted to present operative surfaces traveling in opposite directions, a carrier extending between said wheels for supporting a round body in operative relation to said wheels, 125
15. In apparatus of the general nature of that herein described, in combination, a main frame, a cushioned receptacle mounted on the front portion of said frame, a grinding wheel adapted to be rotated at a relatively high speed, a regulating wheel adapted to be rotated at a relatively low speed, said wheels being adapted to present operative surfaces traveling in opposite directions, a carrier extending rearwardly of said frame and between said wheels for supporting round bodies in operative relation to said wheels, 130

means mounting said grinding wheel with its axis substantially below the path of travel of said body thereby to provide an operative surface inclined away from the operative surface of said regulating wheel, and 5 means causing different portions of said inclined operative surface of said grinding wheel to operate upon said body as said regulating wheel engages irregularities in 10 said body.

15. In apparatus of the general nature of that herein described, in combination, a peripheral grinding wheel adapted to be rotated at a relatively high speed, a regulating wheel adapted to be rotated at a relatively low speed, said wheels being adapted to present operative surfaces traveling in opposite directions, a carrier extending between said wheels and providing a surface for 20 supporting round bodies in operative relation to said wheels, said surface being inclined toward the operative surface of said regulating wheel, and means mounting said grinding wheel with its axis substantially below 25 the path of travel of said body along said carrier thereby to provide an operative surface inclined away from the operative surface of said regulating wheel, said regulating wheel when engaging a projecting irregularity in said body causing said body 30 to ride up on said inclined supporting surface and thereby to be operated upon by a more distant portion of the inclined operative surface of said grinding wheel.

35. 16. In apparatus of the general nature of that herein described, in combination, a grinding wheel adapted to be rotated at a relatively high speed, a regulating wheel adapted to be rotated at a relatively low speed, said wheels being adapted to present operative surfaces traveling in opposite directions, a carrier extending between said wheels for supporting a round body in operative relation to said wheels, means mounting 40 said grinding wheel to provide an operative surface inclined away from said carrier, and means for lifting said body into contact with more distant portions of said operative surface of said grinding wheel when 45 said regulating wheel engages a projecting irregularity in said body.

50. 17. In apparatus of the general nature of that herein described, in combination, a grinding wheel adapted to be rotated at a relatively high speed, a regulating wheel adapted to be rotated at a relatively low speed, said wheels being adapted to present operative surfaces traveling in opposite directions, a pair of relatively fixed posts one 55 on each side of the operative surfaces of said wheels, a carrier for supporting a round body in operative relation to said wheels mounted on said posts and extending between said wheels, and means for vertically 60

adjusting said carrier on said posts relative to one of said wheels.

18. In apparatus of the general nature of that herein described, in combination, a grinding wheel adapted to be rotated at a relatively high speed, a regulating wheel adapted to be rotated at a relatively low speed, said wheels being adapted to present operative surfaces traveling in opposite directions, a pair of relatively fixed posts one 65 on each side of the operative surfaces of said wheels, a carrier for supporting a round body in operative relation to said wheels mounted on said posts and extending between said wheels, and means including an inclined plane for vertically adjusting said carrier on said posts relative to one of said wheels.

19. In apparatus of the general nature of that herein described, in combination, a grinding wheel adapted to be rotated at a relatively high speed, a regulating wheel adapted to be rotated at a relatively low speed, said wheels being adapted to present operative surfaces traveling in opposite directions, a carrier extending between said 75 wheels for supporting a round body in operative relation thereto, and means including a movable wedge for vertically adjusting said carrier with respect to one of said 80 wheels.

20. In apparatus of the general nature of that herein described, in combination, a grinding wheel adapted to be rotated at a relatively high speed, a regulating wheel adapted to be rotated at a relatively low speed, said wheels being adapted to present operative surfaces traveling in opposite directions, a carrier extending between said 85 wheels for supporting a round body in operative relation thereto, means including a movable wedge for vertically adjusting said carrier with respect to one of said wheels, and arranged to move said carrier a given distance in a vertical direction upon a relative movement longitudinally of said wedge greater than said given distance, and means dependent upon the greater relative longitudinal movement of said wedge for providing a visual indication of the height of 90 said carrier with respect to one of said 95 wheels.

21. In apparatus of the general nature of that herein described, in combination, a grinding wheel adapted to be rotated at a relatively high speed, a regulating wheel adapted to be rotated at a relatively low speed, said wheels being adapted to present operative surfaces traveling in opposite directions, a pair of relatively fixed posts one 100 on each side of the operative surfaces of said wheels, a carrier for supporting a round body in operative relation to said wheels mounted on said posts and extending between said wheels, and means for vertically 105

110

115

21. Between said wheels, and means for adjusting the relative inclination between the path of travel of said body along said carrier and the path of the operative surface of said regulating wheel and for vertically adjusting said carrier on said posts with respect to one of said wheels.
22. In apparatus of the general nature of that herein described, in combination, a grinding wheel adapted to be rotated at a relatively high speed, a regulating wheel adapted to be rotated at a relatively low speed, said wheels being adapted to present operative surfaces traveling in opposite directions, a carrier extending between said wheels and adapted to support round bodies in operative relation thereto, means for supporting said carrier, means adapted to guide said bodies onto said carrier and into engagement with said wheels and adjustable toward or away from said carrier, and means for locking said adjustable guiding means and said carrier to said supporting means.
23. In apparatus of the general nature of that herein described, in combination, a grinding wheel adapted to be rotated at a relatively high speed, a regulating wheel adapted to be rotated at a relatively low speed, said wheels being adapted to present operative surfaces traveling in opposite directions, a carrier extending between said wheels and adapted to support round bodies in operative relation thereto, means for vertically adjusting said carrier relative to one of said wheels, means adapted to guide said bodies onto said carrier and into engagement with said wheels, and means for locking said guiding means and said carrier together in position.
24. In apparatus of the general nature of that herein described, in combination, a grinding wheel adapted to be rotated at a relatively high speed, a regulating wheel adapted to be rotated at a relatively low speed, said wheels being adapted to present operative surfaces traveling in opposite directions, a carrier extending between said wheels and adapted to support round bodies in operative relation thereto, means for supporting said carrier, a guiding flange on one side of said carrier, a second guiding flange on the other side of said carrier, said flanges being adapted to guide said bodies on said carrier into engagement with said wheels, means for adjusting one of said flanges toward or away from the other, and means for locking said relatively adjustable flanges and said carrier to said supporting means.
25. In apparatus of the general nature of that herein described, in combination, a grinding wheel adapted to be rotated at a relatively high speed, a regulating wheel adapted to be rotated at a relatively low speed, said wheels being adapted to present operative surfaces traveling in opposite directions, a carrier extending between said wheels and adapted to support round bodies in operative relation thereto, means for adjusting the relative inclination between said carrier and the path of the operative surface of said regulating wheel, means adapted to guide said bodies on said carrier into engagement with said wheels and adjustable toward or away from said carrier, and means for locking said guiding means and said carrier in adjusted position.
26. In apparatus of the general nature of that herein described, in combination, a grinding wheel adapted to be rotated at a relatively high speed, a regulating wheel adapted to be rotated at a relatively low speed, said wheels being adapted to present operative surfaces traveling in opposite directions, a carrier extending between said wheels and adapted to support round bodies in operative relation thereto, means for supporting said carrier, means adapted to guide said bodies on said carrier into engagement with said wheels and adjustable toward or away from said carrier, means adapted to guide said bodies on said carrier after operation thereon by said wheels and adjustable toward or away from said carrier, means for adjusting said carrier with respect to one of said wheels, and means for locking said guiding means and said carrier in adjusted position.
27. In apparatus of the general nature of that herein described, in combination, a grinding wheel, a regulating wheel, means for supporting a round body in operative relation to said wheels, means for driving said grinding wheel at a relatively high speed, means for driving said regulating wheel at a relatively low speed and in a direction to present an operative surface traveling in a direction opposite from that of the grinding wheel, and means for varying the rate of drive of said regulating wheel in said direction.
28. In apparatus of the general nature of that herein described, in combination, a grinding wheel, a regulating wheel, means for supporting a round body in operative relation to said wheels, means for adjusting one of said wheels toward or away from the other, means for driving said grinding wheel at a relatively high speed, means for driving said regulating wheel at a relatively low speed and in a direction to present an operative surface traveling in a direction opposite from that of the grinding wheel, means permitting a positive action of said driving means irrespective of the relative adjustment of said wheels, and means for varying the rate of drive of said regulating wheel in said direction.
29. In apparatus of the general nature of that herein described, in combination, a grinding wheel, a regulating wheel, means

for driving said grinding wheel at a relatively high speed, means for driving said regulating wheel at a relatively low speed and in a direction to present an operative 5 surface traveling in a direction opposite from that of the grinding wheel, means adapted to drive said regulating wheel at a relatively high speed, and manually controlled means for selecting either of said 10 regulating wheel driving means.

30. In apparatus of the general nature of that herein described, in combination, a grinding wheel, a regulating wheel, means for driving said grinding wheel at a relatively high speed, a member driven at a relatively low speed, and a second member driven at a relatively high speed, a third member in driving connection with said regulating wheel, and selectively controlled 15 means for placing said third member in driving connection with either said low speed member or said high speed member.

31. In apparatus of the general nature of that herein described, in combination, a 25 grinding wheel, a regulating wheel, a main driving member adapted to drive said grinding wheel at a relatively high speed, a clutch member driven from said main driving member at a relatively low speed, a second 30 clutch member driven from said main driving member at a relatively high speed, means in driving connection with said regulating wheel, and selectively controlled means for placing said last mentioned means in driving connection with either of said clutch 35 members.

32. In apparatus of the general nature of that herein described, in combination, a grinding wheel, a regulating wheel, means 40 for driving said grinding wheel at a relatively high speed, means adapted to be driven at a relatively high speed and provided with a clutch member, a second clutch member coaxial with said first clutch member 45 and driven from said high speed means at a relatively low speed, and means adapted to place said regulating wheel in driving connection with either of said clutch members.

33. In apparatus of the general nature of that herein described, in combination, a 50 grinding wheel adapted to be rotated at a relatively high speed, a regulating wheel adapted to be rotated at a relatively low speed, said wheels being adapted to present operative surfaces traveling in opposite directions, a carrier extending between said 55 wheels and adapted to support rolls in operative relation thereto, means providing a fixed relative inclination between the path of travel of said rolls on said carrier and the path of said regulating wheel whereby said rolls are given a fixed rate of forward feed 60 between said wheels, and adjustable means for varying said rate of feed of rolls 65 from said fixed rate of feed.

34. In apparatus of the general nature of that herein described, in combination, a grinding wheel adapted to be rotated at a relatively high speed, a regulating wheel adapted to be rotated at a relatively low speed, 70 said wheels being adapted to present operative surfaces traveling in opposite directions, a carrier extending between said wheels and adapted to support rolls in operative relation thereto, means providing a fixed 75 relative inclination between the path of travel of said rolls on said carrier and the path of said regulating wheel whereby said rolls are given a fixed rate of forward feed 80 between said wheels, and means for varying the rate of drive of said regulating wheel to vary said fixed rate of feed.

35. In apparatus of the general nature of that herein described, in combination, a grinding wheel adapted to be rotated at a 85 relatively high speed, a regulating wheel adapted to be rotated at a relatively low speed, said wheels being adapted to present operative surfaces traveling in opposite directions, a carrier extending between said 90 wheels and adapted to support rolls in operative relation thereto, means providing a fixed relative inclination between the path of travel of said rolls on said carrier and the path of said regulating wheel whereby 95 said rolls are given a fixed rate of forward feed between said wheels, and means for varying said fixed rate of feed by adjusting the inclination of said carrier relative to said path of the operative surface of said 100 regulating wheel.

36. In apparatus of the general nature of that herein described, in combination, a grinding wheel adapted to be rotated at a relatively high speed, a regulating wheel 105 adapted to be rotated at a relatively low speed, said wheels being adapted to present operative surfaces traveling in opposite directions, a carrier extending between said wheels and adapted to support rolls in operative relation thereto, means mounting said regulating wheel adapted to provide a fixed relative inclination between the path of its operative surface relative to the path of travel of rolls on said carrier thereby to 110 give said rolls a fixed rate of forward feed between said wheels.

37. In apparatus of the general nature of that herein described, in combination, a grinding wheel adapted to be rotated at a 115 relatively high speed, a regulating wheel adapted to be rotated at a relatively low speed, said wheels being adapted to present operative surfaces traveling in opposite directions, a carrier extending between said 120 wheels and adapted to support rolls in operative relation thereto, means mounting said regulating wheel adapted to provide a fixed relative inclination between the path of its operative surface relative to the path 125 of travel of said rolls on said carrier thereby to give said rolls a fixed rate of forward feed between said wheels.

of travel of rolls on said carrier thereby to give said rolls a fixed rate of forward feed between said wheels, and means for varying the rate of drive of said regulating wheel to vary said fixed rate of feed.

38. In apparatus of the general nature of that herein described, in combination, a main frame, a grinding wheel adapted to be rotated at a relatively high speed, supporting means on said frame for said grinding wheel, a regulating wheel adapted to be rotated at a relatively low speed, said wheels being adapted to present operative surfaces traveling in opposite directions, supporting means on said frame for said regulating wheel, means extending between said two wheels for holding work in operative relation thereto, supporting means for said last-mentioned means, two of said supporting means being movable with respect to the third and in directions to permit adjustment of the distance between said two wheels and of the distance between said work holding means and one of said wheels, and independently operative and coaxial means for adjusting the position of said two movable supporting means with respect to the third supporting means.

39. In apparatus of the general nature of that herein described, in combination, a grinding wheel adapted to be rotated at a relatively high speed, a regulating wheel adapted to be rotated at a relatively low speed, said wheels being adapted to present operative surfaces traveling in opposite directions, a carrier extending between said wheels for supporting round bodies in operative relation thereto, a reservoir adapted to receive a cooling fluid, a pump for circulating said fluid to the operative surfaces of said wheels, and means for conducting said bodies after operation thereon by said wheels into said reservoir, said fluid acting to cushion said reservoir for said bodies.

40. In apparatus of the general nature of that herein described, in combination, a main frame, a grinding wheel adapted to be rotated at a relatively high speed, supporting means on said frame for said grinding wheel, a regulating wheel adapted to be rotated at a relatively low speed, said wheels being adapted to present operative surfaces traveling in opposite directions, supporting means on said frame for said regulating wheel, means extending between said two wheels for holding work in operative relation thereto, supporting means for said last-mentioned means, two of said supporting means being movable with respect to the third and in directions to permit adjustment of the distance between said two wheels and of the distance between said work holding means and one of said wheels, a rotary member having connections with one of said movable supporting means arranged upon rota-

tion thereof to move said supporting means, and a rotary member rotatable about said first-mentioned rotary member arranged upon rotation thereof to move the other of said movable supporting means.

41. In apparatus of the general nature of that herein described, in combination, a grinding wheel, a regulating wheel, and driving means adapted to be connected to a source of power for driving said two wheels and arranged to permit said grinding wheel to be driven at a relatively high speed and said regulating wheel at a relatively low speed but in a direction to present an operative surface traveling in a direction opposite from the direction of the operative surface of said grinding wheel, said driving means including a variable speed mechanism for changing the rate of drive of said regulating wheel.

42. In apparatus of the general nature of that herein described, in combination, a grinding wheel, a regulating wheel, means for holding work of round section in operative relation to said wheels, means for driving said grinding wheel at a relatively high speed, thereby to perform a grinding operation on said work, and means for driving said regulating wheel at a relatively low speed thereby to control the rotation of said work, said last-mentioned means comprising speed-reduction and speed-change mechanism.

43. In apparatus of the general nature of that herein described, in combination, a grinding wheel, a regulating wheel, means for driving said grinding wheel at a relatively high speed, a member adapted to be driven at a relatively low speed, a second member adapted to be driven at a different speed, a third member in driving connection with said regulating wheel, and means controllable at will for placing said third member in driving connection with either said first-mentioned member or said second-mentioned member.

44. In apparatus of the general nature of that herein described, in combination, a grinding wheel adapted to be rotated at a relatively high speed, a regulating wheel adapted to be rotated at relatively low speed, said wheels being adapted to present operative surfaces traveling in opposite directions, means for holding work of round section in operative relation to said two wheels, means for driving said grinding wheel at a relatively high speed, a plurality of members adapted to be driven each at a different peripheral speed, means in driving connection with said regulating wheel, and means for selectively placing said last-mentioned means in driving connection with one of said plurality of members.

45. In apparatus of the general nature of that herein described, in combination, a main frame having supported thereon a

grinding wheel, a regulating wheel adapted to be rotated at relatively low speed, and means for holding work of round section in operative relation thereto; means supported by said main frame and arranged to be driven from a source of power for driving said grinding wheel at a relatively high speed; a plurality of members rotatably supported by said frame and adapted to be driven from said source of power, each of said members having a different peripheral speed; and means for driving said regulating wheel and arranged to be placed at will in driving connection with one of said plurality of members.

46. In apparatus of the general nature of that herein described, in combination, a grinding wheel, a regulating wheel, a carrier for supporting cylindrical bodies in operative relation to said wheels, and means including a pair of coaxially mounted hand-wheels operable from the same portion of the apparatus for independently adjusting each of said wheels toward or away from said carrier.

47. In apparatus of the general nature of that herein described, in combination, a grinding wheel, a regulating wheel, driving means adapted to be connected to a source of power for driving said two wheels, said means including speed change mechanism adapted to permit said grinding wheel to be driven at a relatively high speed and said regulating wheel to be driven at a relatively low speed, and means for varying the rate of drive of said regulating wheel.

48. In apparatus of the general nature of that herein described, in combination, a main frame, a grinding wheel, a regulating wheel, said wheels being adapted to present operative surfaces traveling in opposite directions, a carrier for supporting round bodies in operative relation to said wheels, protective means mounted on said frame for enclosing said wheels, and removable panels mounted on said protective means, each of said panels being substantially opposite one of said wheels to permit access thereto.

49. In apparatus of the general nature of that herein described, in combination, a grinding wheel; a regulating wheel; means for holding work of round section in operative relation to said wheels and arranged to provide a predetermined path of travel for said work past the operative surfaces of said two wheels; means for driving said grinding wheel at a relatively high speed, thereby to perform a grinding operation on said work; means for driving said regulating wheel at a relatively low speed, said wheels being adapted to present adjacent operative surfaces traveling in opposite directions, and the path of travel of the operative surface of said regulating wheel being inclined with respect to said path of travel of

work provided by said work holding means, said last-mentioned driving means including a variable speed mechanism; and means for changing the relative inclination between the path of travel of the operative surface of said regulating wheel and the path of travel of the work provided by said work holding means.

50. In apparatus of the general nature of that herein described, in combination, a grinding wheel, a regulating wheel, a carrier extending between said wheels for supporting round bodies in operative relation to said wheels, and a single movable wedge extending in the direction of said carrier for vertically adjusting said carrier with respect to one of said wheels.

51. In apparatus of the general nature of that herein described, in combination, a grinding wheel, a regulating wheel, a carrier for supporting round bodies in operative relation to said wheels, means adapted to guide said bodies onto said carrier and into engagement with said wheels, precision means for adjusting said guiding means toward or away from said carrier, and means for locking said guiding means in adjusted position.

52. In apparatus of the general nature of that herein described, in combination, a grinding wheel, a regulating wheel, a main source of power adapted to drive said grinding wheel, means driven from said main source of power and adapted to be placed in driving connection with said regulating wheel, and speed reduction gearing driven from said last mentioned means and adapted to be placed in driving connection with said regulating wheel to drive said regulating wheel at a different speed.

53. In apparatus of the general nature of that herein described, in combination, a grinding wheel, a regulating wheel, a main source of power adapted to drive said grinding wheel at a relatively high speed, means driven from said source of power adapted to be placed in driving connection with said regulating wheel to drive said wheel at a relatively high speed and in a direction to present an operative surface traveling in the same direction as the operative surface of said grinding wheel, and speed reduction and reverse gearing adapted to be interposed between said last mentioned means and said regulating wheel to drive said wheel at a relatively low speed and in a direction to present an operating surface traveling in a direction opposite from that of the operative surface of said grinding wheel.

54. In apparatus of the general nature of that herein described, in combination, a main frame, a grinding wheel supported thereby, a regulating wheel on said frame and operatively related to said grinding wheel, a main driving shaft rotatably sup-

- ported by said frame and adapted to be connected to a source of power, driving connections between said shaft and said wheels having included therein speed-change mechanism arranged to permit said grinding wheel to be driven at a relatively high speed and said regulating wheel at a relatively low speed and in respective directions to cause said two wheels to present adjacent operative surfaces traveling in opposite directions, and means extending between said wheels for holding work of round section in operative relation to said two wheels.
55. In apparatus of the general nature of that herein described, in combination, a main frame; a grinding wheel supported thereby; a regulating wheel supported by said frame and operatively related to said grinding wheel; means for holding work of round section in operative relation to said two wheels and arranged to provide a predetermined path of travel for the work past the operative surfaces of said two wheels; a main driving shaft rotatably supported by said frame and adapted to be connected to a source of power; driving connections between said shaft and said wheels having included therein speed-change mechanism arranged to permit said grinding wheel to be driven at relatively high speed and said regulating wheel at a relatively low speed and in respective directions to cause said two wheels to present adjacent operative surfaces traveling in opposite directions, said regulating wheel and said work holding means being related one to the other so that there exists a relative inclination between the path of travel of the operative surface of said regulating wheel and the path of travel of work along said work holding means; and means for changing the relative inclination between the path of travel of the operative surface of said regulating wheel and the path of travel of the work along said work holding means.
56. In apparatus of the general nature of that herein described, in combination, a main frame; a grinding wheel supported thereby; a regulating wheel supported by said frame and operatively related to said grinding wheel; means for holding work of round section in operative relation to said wheels and arranged to provide a predetermined path of travel for the work past the operative surfaces of said two wheels, the path of travel of the operative surface of said regulating wheel being inclined with respect to the path of travel provided for the work by said work holding means, a driving shaft supported by said frame and adapted to be connected to a source of power; driving connections between said shaft and said wheels having included there-
- in speed-change mechanism arranged to permit said grinding wheel to be driven at a relatively high speed and said regulating wheel to be driven at a relatively low speed and in respective directions to cause said two wheels to present adjacent operative surfaces traveling in opposite directions, said driving connections having also included therein mechanism to permit at will a change in the rate of drive of said regulating wheel; and means for changing the relative inclination between the path of travel of the operative surface of said regulating wheel and the path of travel of work along said work holding means.
57. In apparatus of the general nature of that herein described, in combination, a peripheral grinding wheel adapted to be rotated at a relatively high speed, a regulating wheel adapted to be rotated at a relatively low speed, said wheels being adapted to present operative surfaces traveling in opposite directions, and a carrier extending between the operative surfaces of said wheels for supporting a round body in operative relation to the wheels and providing a path of movement for said body in a direction substantially transverse to the axis thereof but inclined with respect to the radius of the grinding wheel to the point of contact thereof with said body.
58. In apparatus of the general nature of that herein described, in combination, a peripheral grinding wheel rotatable at a relatively high speed, a peripheral regulating wheel adapted to be rotated at a relatively low speed, said wheels being adapted to present operative surfaces traveling in opposite directions, a carrier extending between said wheels for supporting a round body in operative relation thereto, and means mounting said wheels with the axis of said regulating wheel at an elevation higher than the elevation of said grinding wheel.
59. In apparatus of the general nature of that herein described, in combination, a peripheral grinding wheel rotatable at a relatively high speed, a peripheral regulating wheel adapted to be rotated at a relatively low speed, said wheels being adapted to present operative surfaces traveling in opposite directions, a carrier extending between said wheels for supporting a round body in operative relation thereto and having a work supporting surface which is inclined with respect to the line joining the axes of said two wheels.
- In testimony whereof, I have signed my name to this specification this twenty-fourth day of January, 1921.

LEWIS R. HEIM.
